UNITED STATES PATENT OFFICE.

HAROLD ROWNTREE, OF CHICAGO, ILLINOIS, ASSIGNOR TO BURDETT-ROWNTREE MANUFACTURING COMPANY, OF CHICAGO, ILLINOIS, A CORPORATION OF ILLINOIS.

CAR DOOR AND STEP OPERATING MECHANISM.

No. 870,051.

Specification of Letters Patent.

Patented Nov. 5, 1907.

*Application filed May 13, 1907. Serial No 373,370.

To all whom it may concern:

Be it known that I, HAROLD ROWNTREE, a citizen of the United States, residing at Chicago, county of Cook, State of Illinois, have made a certain new and useful 5 Invention in Car Door and Step Operating Mechanism, of which the following is a specification.

This invention relates to car door and step operating mechanism.

The object of the invention is to provide means 10 which are simple in construction and efficient in operation for moving a car step into or out of position for use coincidently with the opening or closing of the car door.

A further object is to provide means whereby a car 15 step is moved into or out of position for use coincidently with the opening or closing movement of the car door, the rate of movement of the step varying in constant ratio with relation to the movement of the door.

20 A further object is to provide means whereby when a car door is moved to open position a movable step is automatically moved into usable position, and when the door is closed the step is moved out of usable position the movement of the step being gradually initiated and accelerated.

25 A further object is to provide mechanism having connection with a car door and also with a movable step whereby both the door and the step may be operated thereby.

30 Other objects of the invention will appear more fully hereinafter.

The invention consists substantially in the construction, combination, location and relative arrangement of parts all as will be more fully hereinafter set forth, 35 as shown in the accompanying drawings and finally pointed out in the appended claims.

Referring to the accompanying drawings, and to the various views and reference signs appearing thereon. Figure 1, is a view in side elevation of a car door and a 40 movable step and mechanism for operating said door and step, and embodying the principles of my invention. Fig. 2 is a similar view showing a modified construction embraced within the spirit and scope of my invention. Fig. 3 is a broken detail end view of the 45 step showing the hinged connection thereof.

In the use of car doors and associated movable steps and mechanism for operating the same as heretofore employed, especially where the door and step are moved together, the former into open or closed position 50 and the latter into or out of position for use a sudden increase of power to move the parts is imposed upon the operating mechanism at the instant the step starts to move, thereby causing an uneven and undesirable motion of the door, due to the initial retarding and the 55 subsequent abnormal effect produced. This is partic-

ularly true where pneumatic operating means are employed. During the retarding effect caused by impinging suddenly upon the pneumatic motor the work of initially starting the movement of the step, the operating medium is building up pressure in the motor 60 while the rate of movement of the door is decreased. After this retarding effect is overcome and the movement of the step is accelerated the built up pressure in the motor causes an unduly rapid movement of the door and step and a subsequent slam. It is among the 65 special purposes of my invention to avoid these objections and to this end, I provide means for picking up the step gradually and smoothly thereby avoiding the imposition of a sudden increase of work upon the operating means at the instant the coincident movement 70 of the door and the step is initiated, thereby securing a smooth and regular movement of the door and a relative movement of the door and step in a constantly varying ratio. Many specifically differing means may be employed for accomplishing these desirable results. 75 While, therefore, I have shown and will now describe various constructions for the purpose I desire it to be understood that my invention is not to be limited or restricted, in its broadest scope to the specific details shown and now to be described.

80 Referring to Fig. 1, reference sign A designates a car door, which, in this instance is a sliding door, and B, is the movable car step, in this instance a pivoted folding step. My invention, however, is not to be limited to a sliding door, nor to a folding step. The 85 door and the step may be operated in many different ways. I have shown one arrangement wherein a power cylinder C, is employed, a valve D controlling the supply and exhaust of operating medium to and from said cylinder. The door is operated by means of 90 a rock lever P, pivotally mounted at one end and having sliding connection at the other end to the door. A rod E, connects the lever P, with piston rod F, of the motor cylinder. An actuating rod G, is connected at one end to the car step B, and at the other end at J, 95 to one arm of a bell crank lever K, pivotally mounted as at L. To the other arm of said lever is connected a link M, provided with an elongated slot N, in which operates a pin O, on the door operating lever P. The valve D may be controlled in any suitable or convenient manner, as for instance, by means of a control lever R, and intermediate connections S.

100 In the position of the parts shown in full lines in Fig. 1, the door is closed and the step is folded up, out of the way but in position to move by its own weight 105 into position for use when the door is opened the arrangement being such that as the door begins to open the step begins to move by gravity into usable position. Now when the motor is operated to open the door, or to move the same to open position, as indicated 110

in dotted lines, the operating lever P, begins its rocking movement and the step begins its movement to usable position, but in case the step, for any reason, should stick in its folded up position then when the 5 length of the slot X, has been traversed by pin O, the continued rocking movement of lever P, will cause bell crank lever K, to be rocked about its pivot L, and the rod Q, to be projected in a direction to cause the step B, to be moved into position for use. It will be 10 observed that when the step occupies its position for use the point of connection J, of rod G, the bell crank lever K, the point of connection H, of said rod with the step, and the pivot L, of the bell crank lever, are all practically in the same straight line. Consequently 15 when it is desired to again close the door and move the step out of position for use, or from the position indicated by dotted lines into position indicated by full lines, after the length of slot X has been again traversed by the pin O, but in the reverse direction from 20 that above mentioned the initial movement of the step towards folded up position begins very slowly, by reason of the arrangement of the connection as above explained, and hence a smooth gradual pick up of the step is effected without imposing a suddenly increased 25 load upon the door moving means, and hence insuring a smooth, uniform and certain movement of the door towards closed position without shock or jar. It will also be seen that in the beginning the movement of the door will effect a very slight movement of the step, 30 but as the door approaches its closed position the rate of movement of the step increases in constant ratio of acceleration relative to the movement of the door. By providing the slot X, the door is allowed to partially close before the step begins to move.

35 In the modified form of embodiment of my invention shown in Fig. 2, the door A, step B, motor C, controller R, connections S, valve D, door operating lever P, rod E, piston stem F, and step operating rod G, remain practically and substantially the same as above described.

40 Scribed with reference to the construction and operation pointed out in connection with Fig. 1. Instead of the bell crank lever and slotted link connection as above described, I have shown, in Fig. 2, the rod G, connected at J, to one end of a lever K', pivotally 45 mounted intermediate its ends at L', and having its other end tapered, as indicated at M'. A pin or stud N', on the door operating lever P, is designed to ride over the upper edge of the lever K', as clearly indicated in the drawing and through the rocking move-

50 ment of the lever K', the desired operation of the step effected, the step being folded up or moved out of position for use by the pin or projection N', riding or bearing upon the upper edge of the lever K'. When the door reaches its half closed position the pin 55 or projection N', is just beginning to become effective to rock lever K', and as the door continues to move towards closed position, the movement of the step being towards folded up position is initiated, such movement being very slight at the beginning but as the 60 door approaches its fully closed position the more rapidly the step will be moved. Thus I also secure in this form of apparatus a gradual pick up of the step and an increase in its speed of movement in constant ratio of acceleration relative to the movement of the

door. I also secure an initial movement of the door 65 towards closed position without effecting the movement of the step.

It will be observed that the step operating rod G is connected to the step in such manner that the initial movement of the step out of position for use requires 70 the greatest power, but as the step approaches its folded position the power required to move the step decreases, this decrease in power expended in moving the step would tend to accelerate the movement of the door in closing and therefore to offset this result, I accelerate the speed of movement of the step relatively 75 to the speed of the door and consequently secure an even closing movement of the door.

It is obvious that many other specifically different constructions and arrangements might readily occur to 80 persons skilled in the art and still fall within the spirit and scope of my invention. I do not desire therefore, in the broad scope of my invention, to be limited and restricted to the exact and specific details shown and described. But having shown and described various 85 forms and constructions of embodiments and having described the same, and the purpose, function and mode of operation thereof,

What I claim as new and useful and of my own invention is:—

- 90
1. The combination with a car door and a movable step, of means whereby as the door closes the step is moved, out of position for use, the movement of the step being initiated slowly and thereafter in constant ratio of acceleration relative to the movement of the door.
  2. The combination with a car door and a movable step, of means for gradually initiating a coincident retracting movement of the step as the door closes.
  3. The combination with a car door and a movable step, of operating means for the door and mechanism whereby 100 said operating means gradually initiates a retracing movement of the step as the door closes.
  4. The combination with a car door and a movable step, of intermediate connections for causing coincident movement of said door and step, said intermediate connections 105 effecting a gradual initial movement of the step as the door closes.
  5. The combination with a car door and a movable step, of intermediate connections for coincident movement of said door and step, and means whereby said connections 110 effect an initial closing movement of the door without effecting a movement of the step.
  6. The combination with a car door and a movable step, of intermediate connections for causing coincident movement of the door and step when the door is closed, said 115 means operating to accelerate the movement of the step as the door approaches its closed position.
  7. The combination with a car door, a motor, and connections actuated by the motor for moving the door, of a movable car step, a link connected thereto for moving the 120 same, said link having an elongated slot, and a pin carried by the door moving connections and operating in said slot.
  8. The combination with a car door, and a pivoted lever having sliding connection with the door, whereby, when 125 said lever is rocked the door is moved, of a step, connections operated by said lever for moving the step, and a motor for rocking said lever.
  9. The combination with a car door, and a pivoted lever having operating connection with the door, whereby, when 130 the lever is rocked the door is moved, of a step, lost motion connections between the step and the said lever, and means for rocking said lever.
  10. The combination with a car door and a pivoted lever having operating connection with the door, whereby when 135 the lever is rocked the door is moved, of a step, and de-

5. 11. The combination with a car door and a pivoted lever for moving the same, of a movable step, an operating rod therefor, a bell crank lever to one arm of which said rod is connected, and a link connected to the other arm of said bell crank lever and having a pin and slot connection with the door operating lever.
10. 12. The combination with a car door and moving lever therefor, of a movable step, a bell crank lever, a rod connecting said step and bell crank lever, a link also connected to said bell crank lever, and provided with an elongated slot, a pin carried by the door moving lever, and operating in said slot, and means for actuating said door moving lever.
15. 13. The combination with a movable car door and step of intermediate pivoted connections between the door and
20. step, arranged to be brought into practical dead center alignment when the door is open and the step in position for use.
14. The combination with a movable car door and step or a rod having pivoted connection with the step, pivoted devices intermediate the rod and door, the points of pivotal connections of said devices adapted to be brought into line with each other when the step is in usable position.
25. 15. The combination with a movable car door and a pivoted step and means whereby as the power required to move the step decreases the speed of movement of the 30 step increases relative to the movement of the door.

In testimony whereof I have hereunto set my hand in the presence of the subscribing witnesses, on this 29th day of April A. D., 1907.

HAROLD ROWNTREE.
